PATIENT SUPPORTING AND TRANSPORTING CARRIAGE

David R. Limbach, Fenton, Mich.

Application May 4, 1953, Serial No. 24,824

Term of patent 14 years

(Cl. D83—1)

To all whom it may concern:

Be it known that I, David R. Limbach, a citizen of the United States, residing at Fenton, State of Michigan, have invented a new, original, and ornamental Design for Patient Supporting and Transporting Carriage, of which the following is a specification, reference being had to the accompanying drawing, forming a part thereof.

In the drawings:

Figure 1 is a view in side elevation of a combination patient supporting and transporting carriage, showing my new design;

Figure 2 is a top plan view, and

Figure 3 is an end elevational view thereof.

I claim:

The ornamental design for a patient supporting and transporting carriage, as shown.
